(57) **CLAIM**

The ornamental design for a heating stove, as shown and described.

DESCRIPTION

FIG. 1 is a top perspective view of a heating stove showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of portion 9 of FIG. 1.

The evenly spaced broken lines in the drawings depict the portions of the heating stove that form no part of the claimed design. The dot-dash broken lines framing portions of the claimed design that are illustrated in enlargement form no part of the claimed design.
